Primary Examiner — S. Bryan Reinholdt, Jr.*Assistant Examiner* — James T Tyree(74) *Attorney, Agent, or Firm* — Daryl R. Wright; Greg Carr(57) **CLAIM**

The ornamental design for a model vehicle steering bellcrank as shown and described.

DESCRIPTION

FIG. 1 is an upper, right, front perspective view of a model vehicle steering bellcrank showing our new design; FIG. 2 is an upper, right, rear perspective view thereof; FIG. 3 is a lower, left, front perspective view thereof; FIG. 4 is a lower, left, rear perspective view thereof; FIG. 5 is a front elevation view thereof; FIG. 6 is a rear elevation view thereof; FIG. 7 is a right side elevation view thereof; FIG. 8 is a left side elevation view thereof; FIG. 9 is an upper plan view thereof; and, FIG. 10 is a lower plan view of the model vehicle steering bellcrank.

In the drawings, the broken lines and the unshaded areas within them illustrate portions of the model vehicle steering bellcrank that form no part of the claimed design.
